CYLINDER MOLD PAPERMAKING MACHINE

Charles S. Adams, Holden, Mass., assignor to Rice
Barton Corporation, Worcester, Mass., a corpora-
tion of Massachusetts

Application September 2, 1944, Serial No. 552,509

3 Claims. (Cl. 92—43)

1

This invention relates to paper making ma-
chines and more particularly to a machine of the
type in which paper pulp is laid on the periphery
of a cylinder mold.

The standard cylinder mold machine comprises
a rotatable cylinder having a wire screen sur-
face which is mounted within a vat into which
flows a supply of pulpstock suspended in water.
The water is withdrawn into the interior of the
mold, and the paper web is laid on the revolving
screen surface. In this construction, centrifugal
force set up by the rotating cylinder opposes the
fibre laying operation caused by the inward flow
of water and tends to produce cavitation or
separation of the sheet from the screen surface.
Hence, the speed of the cylinder mold must be
below that at which cavitation may occur.
Moreover, turbulence and a consequent distur-
bance of the paper formation is created by the
cylinder screen surface revolving through the
pulp within the vat, and some of the pulp climbs
up the surface of the screen at the exit side and
tumbles back in a cascade, thus injuring the web
that has been formed. The stock is usually flowed
into the vat at one side and the surplus stock goes
over an overflow dam at the opposite side of the
cylinder. This involves various changes in direc-
tion of the stock flow which also aid in causing
turbulence and disturbing the formation. To
minimize the frictional drag of the cylinder the
stock has been flowed through the vat in the di-
rection of cylinder rotation, yet a turbulence has
resulted from the fact that a large portion of the
stock is passed over an overflow and not all of it
is deposited on the wire. It has also been pro-
posed to widen the vat circle and provide a large
space for the stock so as to minimize turbulence;
but this does not take into account the rotation of
the cylinder through the stock which creates a
frictional drag of the pulp on the web already
laid.

It is the primary object of this invention to
overcome such problems and to provide a cylinder
mold paper making machine in which the paper
web is laid on a revolving screen surface and
which may be operated at a high or a desired
speed and with satisfactory results.

A further object of the invention is to provide a
machine in which the centrifugal force set up by
the revolving cylinder mold is counteracted and
cavitation is prevented.

Another object is to provide a construction of
this type in which all of the pulpstock is laid on
the screen surface and none is required to over-
flow for a recycling operation.

2

A further object is to cause all of the stock to
flow with the revolving wire screen at a rate which
minimizes turbulence and particularly to run the
stock in a thin layer at the same high speed as the
cylinder mold revolves and to cause all of the
stock to be laid on the wire. Further objects will
be apparent in the following disclosure.

According to my invention, I propose to form a
paper web on a cylinder mold screen surface by
10 forcing the stock under a controlled pressure into
a converging throat between an impervious wall
and the cylinder surface and causing all of the
stock to be laid on the screen. The wall is prefer-
ably an endless apron which moves in the same
15 direction and at the rate of the screen.

Referring to the drawings illustrating preferred
forms of the invention:

Fig. 1 is a somewhat diagrammatic vertical and
transverse section through a preferred form of
20 machine;

Fig. 2 is a fragmentary longitudinal vertical
section through the machine;

Fig. 3 is a detail showing the mounting of a
deckle strap and the blanket supporting bars;

25 Fig. 4 is a diagrammatic view of the power
drive;

Fig. 5 is a fragmentary sectional view of a
modification having rolls supporting the apron;
and

30 Fig. 6 is a fragmentary view showing the
mounting of the rolls and associated deckle.

In the embodiment shown in Figs. 1 to 4, the
machine comprises a cylinder mold 10 which may
be of standard construction. This comprises a
35 set of spiders 11 mounted on a driven shaft 12.
A set of longitudinal rods 13 are arranged
peripherally of the cylinder and parallel with the
axis, and they are suitably secured to the spiders.
Surrounding these are coarse and fine mesh
40 screens 14 with the finer mesh screen forming the
outer periphery of the mold. The pulpstock flows
beneath the cylinder and the water passes up-
wardly through the screen mesh into the interior
thereof, and it is withdrawn through a central
45 annular passage. This passage is formed by the
ring 16 (Fig. 2) secured to and revolving with an
end wall 17 of the cylinder. The water passes
into the annular chamber formed by a stationary
ring shaped part 19 and an end wall 20. This
50 space communicates at its bottom with a pipe 21
which leads to a suitable apparatus that serves
to reduce the pressure within the cylinder mold
and to withdraw the water therefrom. The shaft
12 is mounted in suitable bearings 24 carried by a
55 supporting portion of the framework 25, and the

parts may be made in accordance with standard practice.

The primary feature of my invention lies in introducing the pulpstock to the cylinder screen surface through a narrow converging throat 30 formed in part by the cylinder screen 14 and by a travelling endless and impervious apron 32, which may be made of rubber or rubber coated fabric or other suitable material that is capable of holding the pulpstock in position adjacent to the cylinder mold screen surface.

The shape of the throat is defined by the position of the apron adjacent to the mold, and in order that this may be of a definite configuration, I preferably provide a supporting surface, such as a flexible metal plate or cross bars or rolls therebeneath, and the apron is caused to move at such a rate that it tends to hug that supporting surface. The supporting surface shown in Figs. 1 to 3 is formed by a set of independently adjustable cross bars 36 made of suitable material, such as wood. The bars 36 are individually mounted above the walls 38 and 39 of a vat or supporting structure located therebeneath. Each wooden bar 36 is adapted to be moved radially outwardly relative to the axis of the cylinder mold, so that the shape of the throat may be changed and yet provide the apron with a substantially arcuate support. Each bar 36 has at its opposite ends a supporting post 40 secured thereto. This post freely slides in a socket within a bracket member 41 mounted on the wall 39 of the supporting structure, and it is adjusted vertically by means of a screw 42 threaded into the bracket. A set screw 43 serves to fix the post in position.

The opposite sides of this converging throat 30 are enclosed by walls formed by arcuate shaped deckles 45 made of hard rubber or other suitable material. These deckles are shaped to rub against the annular plate 17 and associated parts forming the end of the cylinder and to rub against the endless apron 32 therebeneath, as shown in Fig. 2. The deckle may be secured in place by means of iron brackets 47 fastened to the ends of the cross bars 36 of the apron support. The deckle is adjustably held by means of two screws 48 and 49 carried by the bracket. By this construction, the deckle is moved in and out with the supporting bars 36 when the latter are adjusted, so that it always contacts with the apron. In ordinary practice, the bars 36 would be moved only to a small extent. Various expedients may be employed to prevent leakage of the pulpstock from the throat. The right hand top cross bar 36 (Fig. 1) is located at such a distance from the cylinder surface that there is room only for the passage of the apron 32 and the thickness of paper web laid thereon, so that this end of the tapering throat 30 is thus closed.

The endless travelling apron 32 is driven and supported by a power driven roll 50 at the entrance end of the throat and by a further roll 51, which is preferably power driven, at the exit end of the throat. The apron is further supported in its travel by rolls 52, 53 and 54 which are suitably mounted on the lower framework of the machine. The roll 54 is shown as mounted for adjustment to loosen or tighten the apron. This is accomplished by having its bearing housing 56 provided with a vertical screw threaded passage within which is threaded a screw 57. This screw is carried by two supporting brackets 58 and it is suitably adjusted by the hand wheel 59. The parts are so constructed that turning the hand

wheel serves to move the bearing housing 56 vertically and thus put the proper tension on the apron.

The roll 51 is preferably mounted for adjustment and to be held resiliently against the cylinder 10. Its bearing housings 60 are carried on a pair of levers 61 of the first class which are centrally pivoted at 62 on the framework. The lower end of the lever is pivotally connected to a draw bar 64 which passes through a suitable opening in the frame. A hand wheel 65 tightens the tension of a spring 66 which serves to hold the roll 51 and the apron 32 under a resilient pressure against the cylinder mold, as will be understood.

The leading driving roll 50 may be mounted on the fixed bearing support 68 suitably carried by the framework. The endless apron 32 is held in driving contact with that roll by means of another roll 70 whose bearings are mounted on a pair of levers 72 pivoted at 73 on the framework. This lever is also resiliently and adjustably positioned by means of a draw bar 74 and an adjustable hand wheel 75 and a spring 76, so that the apron is caused to grip the driving roll 50.

A primary feature of this invention involves flowing the pulpstock into the tapering throat 30 at the rate required for laying the web on the wire. It is also preferable that this stock be under a controllable pressure or head. This is accomplished by having the nozzle 80 so shaped as to fit within the space between the apron on the roll 50 and the wire surface of the cylinder, and various expedients may be employed to prevent leakage of stock at this point. The head box 81 has stock supplied to it by means of a valved pipe 82, and suitable regulation of the valve 83 controls the level 84 of the pulpstock in the head box and so regulates the pressure within the throat.

A further feature of this invention involves moving the travelling apron 32 at substantially the same rate as that of the screen surface 14 of the cylinder and causing the pulpstock to flow between these two travelling members at substantially the same rate, so that all of the pulp fibres are laid on the screen surface by the time a given portion of screen reaches the narrow or closed end of the throat. Various expedients within the knowledge of those familiar with paper making practice may be adopted for driving the cylinder 10 and the rolls 50 and 51, such as the standard sectional electric drive employed for driving the different rolls of a Fourdrinier paper machine, which includes synchronous motors and resistance controls so arranged that the surface speeds of the various members may be synchronized or controlled. As illustrated in Fig. 4, the roll 50 supported on its bearings 68 may be driven through a speed reduction mechanism 91 by an electric motor 92. The cylinder 10 carried on suitable bearings 24 may be driven through a speed reduction gear mechanism 94 by means of an electric motor 95. Also, the roll 51 carried by bearings 60 may be driven through a speed reduction gear mechanism 96 by means of an electric motor 97. The speed reduction mechanisms are so constructed that when the motors are synchronized they drive the different elements at the same surface rate. It is desirable that the motor 92 which drives the roll 50 give a slightly greater torque than required so that it tends to feed the apron at a faster rate than it 75 is withdrawn by the driven roll 51, so as to insure

that the apron 32 is held against the supporting structure 36 and does not constrict the throat 30. The cross bars 38 which form the supporting structure for the apron 32 are spaced apart somewhat so that no air or water pockets can prevent the apron from hugging closely to the support. Air and leakage water may be exhausted from the vat through opening 98.

I may also use a set of supporting rolls, as illustrated in Figs. 5 and 6, for supporting the apron 32. In order that each of these rolls 100 may be adjustably positioned, its mandrel may be supported at each end in a bearing 102 (Fig. 6) which is carried on a post 104 that is movable radially of the cylinder 10 the same as are the bar supports 40 above described. That is, the post 104 slides in a socket within the bracket 106 mounted on one of the walls of the vat, and the post is vertically adjusted by means of the screw 107 and locked in place by the set screw 108. The deckle construction may be as above described, and wherein the stationary deckle 110 is carried by an iron bracket 111 likewise mounted on the top of the bearing structure 102 so that the deckle may be vertically adjusted with the roll 106. These rolls 100 carry the apron without material frictional drag, since they are freely rotatable and move therewith.

Since the paper web is laid on the wire screen of the cylinder, it clings to that wire surface after it has broken contact with the apron 32 when the latter passes over the roll 51. The paper web is stripped from the cylinder 10 by means of an endless blanket 115 which may be made of felt or other suitable material. This blanket passes over a roll 116 suitably mounted on the framework and receives the paper web 118 and transports it to the next stage of treatment. The roll 116 may have its bearings 119 suitably mounted on a lever 120 pivoted at 121 on the framework, and the lower end of this lever is resiliently and adjustably positioned by means of a draw bar 123 pivotally connected to the lever and adjusted by means of a hand wheel 124 which compresses a spring 125 and thus holds the blanket tightly against the paper web on the cylinder mold.

The operation of the machine will be apparent in the above disclosure. Pulpstock is introduced under the pressure of such head as is provided by the head box, and the stock flows through the pipe 80 into the converging throat 30 between the impervious apron 32 and the screen surface 14 of the cylinder. The cylinder periphery and the apron are preferably moving at the same surface rate and the stock enters the throat at substantially that rate so that there is no material frictional drag on the paper web. The water is withdrawn rapidly through the screen surface of the cylinder and removed through the outlet pipe 21. The paper fibres are laid on the cylinder screen as the stock becomes concentrated through the removal of the water. The fibres retain their criss-cross haphazard and interlaced arrangement as the water is removed, since there is no frictional drag at any point which would tend to straighten out the fibres, except as they are drawn radially towards the cylinder surface. All of the pulp fibres are laid on the screen of the cylinder since there is no provision for overflow of surplus stock. The atmospheric pressure within the cylinder may be reduced to that degree which causes not only an effective removal of the water but also a partial drying of the web. Since the apron 32 has an

impervious surface and the water is removed upwardly through the screen of the cylinder, the web is laid wholly on the cylinder; and the apron serves merely as a travelling wall defining the bottom of the cavity or tapering throat 30 which holds the paper stock during the web formation. The cylinder 10 may have a diameter of from 3 to 8 feet, and the arcuate tapering throat extends for a considerable distance around the cylinder and which is sufficient for the paper laying operation. Since the opposed walls formed by the cylinder wire 14 and the apron 32 are moving at the rate of the pulp flow, the pulp is substantially quiescent relative to the walls of the throat. Consequently the intermatting of the fibres or the texture of the paper is determined chiefly by the fact that the fibres are drawn out of suspension by the water moving radially through the cylinder wall. The rate of paper making is determined primarily by the hydrostatic head of the pulp and the rate of movement of the screen 14, as well as the rate at which the water can escape from the throat.

It will now be appreciated that various modifications may be made in the construction and equivalent features substituted for those above described. Also, the paper maker may control the texture of the paper and the rate of its formation by varying the shape of the throat and the head of the pulpstock supplied thereto as well as by varying the rates of the moving parts. The above disclosure is, therefore, to be interpreted as illustrating the principles of this invention and my preferred embodiments thereof and not as imposing limitations on the claims appended hereto.

I claim:

1. A cylinder mold paper making machine comprising a rotatable hollow cylinder mold having a pervious, fine mesh wire screen surface arranged for the formation thereon of a paper web deposited from an aqueous suspension of paper pulp stock, means for removing water from the mold interior, means including an endless, impervious, traveling wall beneath and spaced from the mold periphery which forms therewith an arcuate tapering throat of fixed configuration converging from a wide stock entrance to a closed end where the paper on the wire contacts with the wall, an adjustable support for said wall located beneath the mold which predetermines the shape of said wall and the size of the throat, controllable driving mechanism for moving the cylinder periphery and the wall towards the closed end of the throat at the same rate, regulatable means including a conduit having a substantially water-tight connection with the wide end of the throat for supplying an aqueous pulp suspension and maintaining the throat filled under a predetermined hydraulic pressure in the throat, means including a valve in said conduit for varying said hydraulic pressure and governing the rates of water removal and the formation of a paper web which causes the pulp suspension to move beneath the mold as a substantially quiescent body at about the same rate as that of the cylinder periphery while the water is removed upwardly through the cylinder mold wall, and means for removing the paper web from the mold outside of the throat.

2. Apparatus according to claim 1 in which said support comprises spaced, adjustably mounted rolls beneath the cylinder which carry the moving wall adjacent the throat.

3. A cylinder mold paper making machine comprising a rotatable hollow cylinder mold having

a pervious, fine mesh wire screen periphery arranged for the formation thereon of a paper web deposited from an aqueous suspension of paper pulp stock, means for removing water from the mold interior, means including an endless, impervious, traveling wall beneath and spaced from the mold periphery which forms therewith an arcuate tapering throat of fixed configuration converging from a wide stock entrance at one side of the mold to a closed end at the other side where the paper on the wire contacts with the wall, a support for said wall located beneath and spaced from the mold which predetermines the position of the wall and the shape of the throat, controllable driving mechanism for moving the cylinder mold periphery and the wall simultaneously towards the closed end of the throat at the same rate, regulatable means including a conduit having a substantially water-tight connection with the wide entrance of the throat for introducing an aqueous paper stock suspension and maintaining the throat filled under a controlled hydraulic head which causes the pulp stock to move along the throat at substantially the rate of the mold periphery and which forces the water from the throat upwardly through the periphery of the cylinder mold screen at a rate governed by the head and so causes the deposition on the under

5 face of the mold of all of the introduced stock as the required paper web, and means for progressively removing the web from the mold periphery after it has been transported from the throat.
